UNITED STATES PATENT OFFICE.

GEORGE B. THOMAS AND CARL ERIC ANDERSON, OF BRIDGEPORT, CONNECTICUT,
ASSIGNORS TO THE BRYANT ELECTRIC COMPANY, OF BRIDGEPORT, CONNECTICUT, A CORPORATION OF CONNECTICUT.

PULL-SOCKET.

1,333,352.

Specification of Letters Patent.

Patented Mar. 9, 1920.

Application filed August 25, 1914. Serial No. 858,532.

To all whom it may concern:

Be it known that we, GEORGE B. THOMAS and CARL ERIC ANDERSON, both citizens of the United States of America, residing in the city of Bridgeport, in the county of Fairfield and State of Connecticut, have invented certain new and useful Improvements in Pull-Sockets, of which the following is a specification.

10 Our invention relates to pull sockets and particularly to the switch mechanism thereof, the object of our invention being to provide a switch device adapted to effect a quick double make and break of the socket circuit, with a wide parting between the switch terminals and switch plate whereby a relatively heavy current may be safely broken.

In the accompanying drawing,
20 Figure 1 is a vertical section through a pull socket in which our invention is embodied in one form;

25 Fig. 2 is a dropped perspective of certain of the elements of the switch mechanism; Fig. 3 is a similar view of the actuating ratchet and associated parts;

Fig. 4 is a plan of the upper button;

Fig. 5 is an inverted plan of the socket with the shell removed;

30 Fig. 6 is a plan of the lower insulating button;

Fig. 7 is an inverted plan of the upper button;

35 Fig. 8 is a detached perspective of one of the wire terminals and its associated switch terminal; and

Fig. 9 is an inverted perspective of the operating plate shown in Fig. 3.

The present switch mechanism is here shown mounted in a pull socket, the insulating body of which comprises an upper button A and a lower button B mounted as usual within a casing comprising a cap 10, shell 11 and insulating lining 12 within the latter. The screw shell 13 is secured to the lower button B by screws 14, 15 passing through the reinforcing yoke 16, the screw 14 engaging the base of the wire terminal 17 to which one of the leading-wires is connected. The center contact 18 is riveted to the button B and its base is angled upward through the passage 19 into the switch chamber where its end 20 forms one of the switch terminals engaged

by the switch bar 21. The other switch terminal 22 passes through an aperture 23 in the button B and is secured by the screw 24 which passes through its base and the angled base of the standard 25 which forms the other wire terminal. It is obvious that in the position shown in Fig. 1 in which the switch bar 21 connects the switch terminals 20 and 22, the current is led from the wire terminal 25 to the center contact 18, while in its other position at right angles to that shown in Fig. 1, the center contact circuit is broken at each end of the switch bar 21. The double break thus secured is very wide and a relatively heavy current can be safely broken by the switch.

The mechanism for operating the switch bar 21 comprises an escapement mechanism mounted on the spindle 26. The stop plate 27 with four stop shoulders 28 is here shown riveted to a base plate 29 having downwardly extending lugs 30 which take into recesses 31 in the button B, thus holding the stop plate 27 stationary. The spindle 26 passes down through a central perforation 32 in the stop plate into a socket 33 in the button B. Mounted on the spindle 26 we provide a cam 34 bearing within the cam plate 35. The latter is provided with a downwardly-extending stop lug 36 adapted to operate with the shoulders 28 of the stop plate 27 and an upwardly extending lug 37 which slides in the slot 38 of the switch bar 21, the latter in normal position lying above the cam 34 on the switch spindle 26. The switch spring 39 is coiled upon the spindle 26 and is provided at its lower end with a loop 40 which engages the lug 41 struck up from the switch bar. A second loop 42 at the upper end of the switch spring engages one of the downwardly struck lugs 43 on the star plate 44. A disk 45 is rigidly mounted upon the spindle 26 in like manner as the cam 34 by means of a radial slot 46 passed through tangential slots 47 on opposite sides of the spindle and swaged tightly in position. Through peripheral notches 48 in this disk the lugs 43 on the star plate 44 project downwardly into position in which they may be engaged by the loop 42 of the switch spring. It is thus obvious that both the disk 45 and the star plate 44 rotate with the switch spindle 26. Radial arms 49 on

the star plate 44 are engaged by the dogs 50 struck up from the coöperating ratchet plate 51 mounted on the segmental operating plate 52 of insulating material to the 5 margin of which the chain rail 53 is secured. The central perforation 54 in the ratchet plate 51 affords a bearing therefor on the spindle 26. A return spring 55 is mounted upon the spindle above the operating plate 52 and is operatively engaged to the latter through the loop 56 at the lower end of the spring which engages the tongue 57 struck up from the ratchet plate. The upper end of the spring 55 passes through 10 a hole 58 in the flange of the socket bearing 59 for the upper end of the spindle 26. Inasmuch as this flange, which is noncircular, is seated in a recess 60 of like shape, it is held normally against rotation. It may 15 be depressed out of this recess, however, and turned in either direction to adjust the tension of the spring 55, after which it is again seated in its recess.

The operation of the switch will be readily understood. Upon a pull of the chain 61 through the chain guide 62 the operating plate 52 is moved in a direction to effect engagement between the dogs 50 on the ratchet 21 51 and the arms 49 on the star plate 44. Inasmuch as the latter is rigid with the spindle 26, the latter is rotated. The spring 39 is simultaneously placed under tension by its engagement with the lugs 43 since the lower 21 end of the spring engages the switch bar 21 35 which is held stationary by reason of the engagement of the lug 36 on the cam plate with one of the stop shoulders 28. As the spindle rotates, however, the cam 34 thereon forces the cam plate 35 outward, thus freeing 40 the lug 36 from the shoulder 28 and permitting it to rotate with the switch bar. As it rotates, however, the cam plate is drawn inward by reason of the shape of the cam 34 and the lug 36 engages the succeeding 45 shoulder 28, thereby halting the switch bar after a quarter revolution thereof. The switch bar having thus taken its "on" or "off" position, as the case may be, the pull chain 61 is released and the operating plate 50 is returned by the spring 55 to its original position ready to again operate the switch.

Various modifications of construction will readily suggest themselves and we do not limit our invention to the details shown.

We claim as our invention:—

1. In an electric switch, a switch spindle, an actuating ratchet plate oscillating thereon, a marginally notched washer fast on the spindle, a star plate having radial arms adapted to coöperate with the dogs of the ratchet plate, and offset fingers adapted to engage the notches of the washer on the spindle, in combination with a spring tensioned by the rotation of said parts.

2. In an electric switch, a switch spindle, a switch bar freely journaled thereon, and comprising a strap having its ends offset to form contact wings, the body of said bar being slotted at one side of its axis of rotation, and having a lug struck therefrom on the opposite side of said axis of rotation, a switch spring coiled on the spindle and engaging said lug on the switch bar, in combination with a catch plate freely surrounding the spindle and having a lug offset into engagement with the slot in the switch bar, a stop lug offset in the opposite direction, a serrated stop plate engaging the stop lug, and a cam fast on the spindle and engaging the catch plate and serving on the rotation of the spindle to free the stop lug of the catch plate from the serrated stop plate, substantially as described.

3. In an electric lamp socket, an insulating button pierced on opposite sides of the axis of the socket, a center contact having an offset arm projecting through one of said holes in the button, a switch terminal projecting through the other hole in said button, a wire terminal electrically connected to said switch terminal, and a rotary switch bar adapted to make and break connection between the center contact arm and switch terminal, substantially as described.

In testimony whereof we have signed our names to this specification in the presence of two subscribing witnesses.

GEORGE B. THOMAS.
CARL ERIC ANDERSON.
